ROBERT ESNAULT-PELTERIE, OF PARIS, FRANCE.

MEANS FOR REGULATING THE OUTPUT OF PUMPS OPERATED BY THE ENGINES OF AUTOMOBILES OR THE LIKE.

Application filed August 16, 1921. Serial No. 492,855.

To whom it may concern:

Be it known that I, ROBERT ESNAULT-PELTERIE, a citizen of the Republic of France, residing in Paris, France, have invented new and useful Improvements in Means for Regulating the Output of Pumps Operated by the Engines of Automobiles or the like, which is fully set forth in the following specification.

10 This invention consists in an improved method and means for controlling the liquid output of a pump, a method of control by which the output can be varied both automatically and at will, as will be explained later, and this by simple mechanical means which provide for a progressive and automatic change of speed of automobiles.

According to the present invention, the variation of the output of a pump is obtained by the employment of an auxiliary piston having a variable stroke, the output of which reduces that of the pump working piston. When the two outputs are equal, the total output will be nothing and, on the contrary, when that of the auxiliary piston is nothing the total output would be equal to that of the working piston.

The principal feature of the present invention consists in the simplicity of the means for accomplishing this result, the auxiliary piston being driven without the aid of any mechanical member and simply by means of the pressure developed in the body of the pump.

35 This auxiliary piston should have a large surface and a small stroke, so that only a small inertia is developed by its movement even when the latter is rapid. This allows its strokes to be controlled by an adjustable abutment, for example a screw, without the shock at the end of the stroke giving rise to any considerable absorption of energy.

If it becomes necessary to further diminish this small loss of work, it would be easy to arrange the abutment as an elastic member (on account of the short stroke and the correspondingly small momentum, a small elasticity will be sufficient).

50 The screw of the abutment can be controlled directly by hand or by the intervention of a servo-motor. The description which follows with respect to the accompanying drawing, given by way of example, will explain the manner in which the invention is carried out.

Fig. 1 is a section of an improved pump according to the invention; Fig. 2 is a section showing the control of the screw of the abutment by a servo-motor; Fig. 3 is a section on the line X—X of Fig. 1.

As shown in Fig. 1, the pump consists of a box or casing 1 separated by a partition 2 into two parts provided respectively with an outlet 3 and an inlet 4.

60 The flaps or valves of delivery 5 and of suction 6 of each pump body are annular and formed by sheets of steel of small thickness (or example, 0 m/m 2 each) secured between two pieces 7 and 8, threaded one on the other and forming the seat of the valve, the circular pieces 8 being provided with arms, not shown in the drawing, which attach them to the pieces 7. As shown in Fig. 3 the valves 5 which are annular, carry openings 9 disposed circularly in such a manner that the annular part interior to these openings is held between pieces 7 and 8 and the exterior annular part forms the valve at the edges of the pieces 7 and 8.

65 The two dotted circles of Fig. 3 represent the edges of the annular hole for the oil. The suction valves 6 are mounted in a similar manner between pieces 7 and 8, but it is the exterior annular part which is held between these pieces, the openings 9 being disposed towards the periphery, while the suction of the oil takes place through an annular surface nearer the centre.

70 The two dotted circles of Fig. 3 represent the edges of the annular hole for the oil. The suction valves 6 are mounted in a similar manner between pieces 7 and 8, but it is the exterior annular part which is held between these pieces, the openings 9 being disposed towards the periphery, while the suction of the oil takes place through an annular surface nearer the centre.

75 The two dotted circles of Fig. 3 represent the edges of the annular hole for the oil. The suction valves 6 are mounted in a similar manner between pieces 7 and 8, but it is the exterior annular part which is held between these pieces, the openings 9 being disposed towards the periphery, while the suction of the oil takes place through an annular surface nearer the centre.

80 The two dotted circles of Fig. 3 represent the edges of the annular hole for the oil. The suction valves 6 are mounted in a similar manner between pieces 7 and 8, but it is the exterior annular part which is held between these pieces, the openings 9 being disposed towards the periphery, while the suction of the oil takes place through an annular surface nearer the centre.

85 The two dotted circles of Fig. 3 represent the edges of the annular hole for the oil. The suction valves 6 are mounted in a similar manner between pieces 7 and 8, but it is the exterior annular part which is held between these pieces, the openings 9 being disposed towards the periphery, while the suction of the oil takes place through an annular surface nearer the centre.

90 The two dotted circles of Fig. 3 represent the edges of the annular hole for the oil. The suction valves 6 are mounted in a similar manner between pieces 7 and 8, but it is the exterior annular part which is held between these pieces, the openings 9 being disposed towards the periphery, while the suction of the oil takes place through an annular surface nearer the centre.

95 The two dotted circles of Fig. 3 represent the edges of the annular hole for the oil. The suction valves 6 are mounted in a similar manner between pieces 7 and 8, but it is the exterior annular part which is held between these pieces, the openings 9 being disposed towards the periphery, while the suction of the oil takes place through an annular surface nearer the centre.

100 The two dotted circles of Fig. 3 represent the edges of the annular hole for the oil. The suction valves 6 are mounted in a similar manner between pieces 7 and 8, but it is the exterior annular part which is held between these pieces, the openings 9 being disposed towards the periphery, while the suction of the oil takes place through an annular surface nearer the centre.

with the lever arm 20. It is this piece 16 which constitutes the adjustable abutment for the piston.

The cavity 21 communicates by the pipe 22 5 with the suction chamber 23 of the pump. Preferably at this pipe and near the chamber 23 an air chamber, not shown, should be arranged.

It should be remarked that the end of the 10 plunger piston 24 of the oil pump is in the form of a very prolonged cone. This is of great importance in order to avoid shocks and to allow the action to take place at very high speeds.

15 Obviously, the plunger piston should be guided in a perfect manner and for this reason it can be terminated in a crosshead 25 sliding in guides 26, which can be placed on the fixed base of the body of the suction 20 pump or can be cast with it. The cross-head of the piston can then be connected by a connecting rod 27 and a crank to the shaft of any motor. It will be understood that it may in certain cases be advantageous, notably 25 for effecting the change of speeds of automobiles, to group in a single block a motor with four cylinders and two pumps, so that the design is similar to the general arrangement of a motor with six cylinders.

30 There is also an advantage which is easily understood, in making such pumps work in groups of two 180° apart, in order that the successive work of delivery and suction in each of them shall be intercalated respectively; in this way the variation of the total 35 output is very much reduced. By means of groups of three at angles of 120° the output would be still more regular (and in the same way in proportion as the number of pumps 40 working together is increased).

As always, if the number of the pumps is restricted, the output will undergo sensible variations, it is advisable to arrange on the delivery pipe 3 and on the suction pipe 4 45 and in the neighbourhood of the pump, air chambers or preferably pistons resting on suitable springs which permit them to circulate a volume at least equal to half the cylinder of the plunger piston 24, in the case 50 of a single pump, or a sufficient fraction of this cylinder in the case of several pumps working together. In order to control the lever 20, which is integral with the screw 19 which controls the stroke of the compensating piston 10, any mode of regulation can 55 be used. It is sufficient to work this lever by any means suitable for turning the screw 19 and to lower it more or less. The regulation of this lever may be effected by a 60 servo-motor such as represented in Fig. 2. By this means, the distribution valve 32 of the servo-motor is exposed on its face 33 to the pressure of a tachymetrical centrifugal pump keyed on the shaft of the motor and 65 on its other face 34 to the pressure of a

spring, of which the tension is regulated by the displacement of the piece 35 by means of the hand lever 29. The space comprised between the piston 35 and the valve 32 is in communication by a pipe 36 with the suction of the tachymetrical centrifugal pump. This valve 32 is provided with two bent 70 passages 37, 38 which, during the displacement of the said valve, register with extensions of the pipes 39, 40 and 41, the two first 39, 40 leading to the front end of a cylinder 42, and the third 41 to the rear end of the said cylinder 42. In the cylinder, a movable piston 44 has its piston rod 43 connected to the arm 20 and consequently determines the angular movement of the screw 19.

It will be seen that when the tension of the spring has been regulated by displacing the piston 35 by the aid of the hand lever 29, the arrangement of this servo-motor constitutes a speed regulator affecting the power absorbed by the pump by the control of the output of oil. When, in fact, the speed of the motor increases, the pressure 85 of the oil acting on the face 33 of the valve 32 increases since the centrifugal pump turns more quickly. The slide valve 32 is then displaced towards the left, compressing the spring, and the oil passing through the passages 38 and 41 drives the piston 44 90 towards the left, which turns the screw 19.

Obviously, the connections will be so arranged that when the speed of the motor increases and consequently the pressure 100 rises in the tachymetrical pump, the screw 19 is drawn down in the direction which causes it to approach the piston 10, thus diminishing the stroke of the latter and augmenting relatively the output of the 105 pump, while increasing the power absorbed.

By moving the hand lever 29, the tension of the spring can be varied, which causes the small movable piston to take up different positions of equilibrium corresponding 110 to different speeds of the motor.

It is evident that the present invention is not limited to the arrangement shown, but that it can be applied to any type of pump wherein an end or movable part has a small 115 and variable stroke, so that the output of the said pump may be varied automatically or at will.

This automatic variation of the output permits, as has been said, of a progressive 120 and automatic change of speed of automobiles. In fact, if the respective pump or hydraulic motor which drives the wheels is restricted so as to have an invariable output, when the vehicle approaches an incline, 125 the following phenomena will occur.

As the resisting torque of the wheels increases, the pressure at the admission of the motor pumps increases proportionately; that is to say, at the delivery of the gener- 130

ator pumps which are the object of the present invention. The resisting torque opposed to the motor by the generator pump then increases equally and the said motor 5 has a tendency to slow down. As soon as it slows down, the control of the movable abutment acts, as has been explained, in lessening the active surface of the cylinder of the generator pump, until the motor 10 has taken up the speed which the position of the hand lever 29 of Fig. 2 assigns to it. The output being thus lessened, the speed of the vehicle diminishes in the same proportion; the speed of the motor thus remaining constant.

It is seen that in this way the hand lever 29 of Fig. 2 determines at will the speed system of the motor depending on the position occupied by the said hand lever, the 20 speed being constant for each position. It will thus be perceived that the variations of speed of the vehicle are obtained by the variations of admission to the motor, while the speed of rotation in the said motor 25 remains constant during these changes of speed of the vehicle.

It is evident that it would be possible to give the motor a single speed and not several speeds.

30 In this case hand lever 29 could be eliminated and the end 35 of the cylinder made immovable, the spring which balances the pressure of the tachymetrical pump having a tension suitably adjusted beforehand, in order that the motor should turn at the desired speed.

The control system in question presents the great advantage in its application to driving the screws of aeroplanes that the hand lever 29 of Fig. 2 can be placed in the position which determines the speed of rotation of the motor which is most favourable and that then the screw automatically takes the speed for which it absorbs the corresponding power.

Having now particularly described and ascertained the nature of my said invention and in what manner the same is to be performed, I declare that what I claim is:—

50 1. In a pump provided with a piston and actuated by a motor, a second piston and automatic means controlled by the motor for limiting the stroke of the second piston and for varying the output of the pump.

55 2. In a pump provided with a piston and actuated by a motor, a second piston having a large surface compared with that of the first piston and movable over a short length compared with the stroke of the first piston, by the direct action of the pressure of the liquid in the pump body, whereby the second piston will absorb but a small amount of visviva as compared with the energy transmitted by the pump, whose output is modified.

3. In a pump provided with a piston and actuated by a motor, a second piston having a large surface compared with that of the first piston and movable, over a short length compared with the stroke of the first piston, 70 by the direct action of the pressure of the liquid in the pump body, resilient means for limiting the stroke of the second piston in order that the movement of the piston and the shocks at the end of the stroke shall absorb but a small part of the energy transmitted by the pump, whose output is modified. 75

4. A pump comprising a cylinder filled with liquid, a piston movable in said cylinder, a conical end formed on said piston whereby eddies in the liquid are prevented during high speed motion, suction and delivery flap valves, a second piston having a large surface compared with that of the first piston and movable, over a short length compared with the stroke of the first piston, 80 by the direct action of the pressure of the liquid in the pump body, resilient means for limiting the stroke of the second piston in order that the movement of the piston and the shocks at the end of the stroke shall absorb but a small part of the energy transmitted by the pump whose output is modified. 85

5. A pump comprising a cylinder filled with liquid, a piston movable in said cylinder, a conical end formed on said piston, whereby eddies in the liquid are prevented during high speed motion, suction and delivery flap valves, a second piston having a large surface compared with that of the first piston and movable over a short length compared with the stroke of the first piston, a screw-threaded rod screwed into the bottom of the cylinder for the purpose of limiting the stroke of the latter, and means for automatic rotation of the screw-threaded rod and for thereby varying the output of the 90 pump. 95

6. System of transmission of a driving effort, comprising in combination a motor, a generating pump adapted to be driven by said motor, a piston movable in the pump cylinder, a liquid filling the cylinder, a second piston disposed in the second cylinder and movable by the pressure of the liquid, suction and delivery flap valves, a passage 100 communicating with the delivery valves, a power pump of known type communicating with said passage and adapted to overcome the resistance by performing a certain work, a screw-threaded rod disposed in the end of the cylinder of said generating pump, said rod serving to limit the stroke of the second piston of the generating pump, a servomotor controlled by the speed of the motor and acting upon the screw-threaded rod in 105 order to vary the output of the generating 110 pump. 115

120

125

130

pump according to the speed of the motor, whereby the motor shall be enabled to maintain its normal speed irrespectively of the resistance to be overcome by the power pump.

7. System of transmission of a driving effect, comprising in combination a motor, a generating pump adapted to be driven by said motor, a piston movable in the pump cylinder, a liquid filling the cylinder, a second piston disposed in the second cylinder and movable by the pressure of the liquid, suction and delivery flap valves, a passage communicating with the delivery valves, a power pump of known type communicating with said passage and adapted to overcome the resistance by performing a certain work, a screw-threaded rod disposed in the end of the cylinder of said generating pump, said

rod serving to limit the stroke of the second piston of the generating pump, a tachymetrical centrifugal pump keyed on the motor shaft, a cylinder containing a piston, a passage effecting communication between the liquid discharged by the centrifugal pump and the surface of the piston, a spring with adjustable tension adapted to act upon the other surface of the piston, conduits formed in the body of the piston, a second cylinder communicating with said conduits of the piston, a piston movable in a second cylinder, a rod integral with the piston and adapted to act upon the rod screwed into the end of the cylinder of the generating pump.

In testimony whereof I have signed this specification.

ROBERT ESNAULT-PELTERIE.
